[57] CLAIM

The ornamental design for a movable skid lift, as shown and described.

DESCRIPTION

FIG. 1 is a perspective view of a movable skid lift showing my new design;

FIG. 2 is a side elevational view with the opposite side being a mirror image thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view of a second embodiment of the design shown in FIG. 1;

FIG. 8 is a side elevational view thereof; and,

FIG. 9 is an opposite side elevational view thereof.

FIG. 1.

FIG. 3.

FIG. 2.

FIG. 5.

FIG. 4.

FIG. 6.

FIG. 7.

FIG. 8.

FIG. 9.
